COMBINATION SQUARE

Ernest Keszler, 3525 Broadway, Chicago, Ill.

Filed Nov. 13, 1961, Ser. No. 67,480

Term of patent 14 years

(Cl. D52—6)

FIG. 1 is a perspective view of a combination square showing my new design;

FIG. 2 is a side elevational view thereof with the rule omitted, shown on a somewhat enlarged scale;

FIG. 3 is a left end elevational view of FIG. 1 on a reduced scale;

FIG. 4 is an enlarged fragmentary perspective view thereof; and

FIG. 5 is a top plan view thereof with a portion of the rule broken away for convenience of illustration and shown on a reduced scale.

The undisclosed side of the combination square is substantially the same in appearance as the side seen in FIG. 1.

I claim:

The ornamental design for a combination square, as shown and described.
